UNITED STATES PATENT OFFICE

2,507,061

TIE FOR WALL FORMS

Arthur H. Symons, Chicago, Ill.

Application June 13, 1945, Serial No. 599,148

7 Claims. (Cl. 24—1)

1

The present invention relates generally to wall forms. More particularly the invention relates to that type of wall form which is primarily designed and adapted for use in the formation of a concrete wall or like structure and as its components comprises: (1) a pair of opposed, spaced apart series of upstanding abutting panels of the rectangular frame and facing variety; (2) a plurality of horizontally disposed combined tie and spreader rods which extend between the two series of panels and have the ends thereof provided with loops and extending through holes in the facings of the panels; and (3) a plurality of devices which are in the form of brackets on the panel frames and slidably mounted loop receiving bolts on the brackets and serve releasably to lock the ends of the combined tie and spreader rods to the panels in order to hold the two series of panels against relative lateral displacement in connection with pouring of concrete therebetween for wall forming purposes.

One object of the invention is to provide a wall form of this type which is an improvement upon, and has certain inherent advantages over, previously designed wall forms of the same general character, is characterized by the fact that the devices for releasably locking the loop equipped ends of the combined tie and spreader rods to the panels are so designed and constructed that they effectively and efficiently fulfill their intended purpose and permit the wall form as a whole to be assembled and dismantled with facility, and is further characterized by the fact that the brackets of the releasable locking devices are so arranged, constructed and designed that they may be permanently attached to the frames of the panels and their outer portions are substantially flush with the outer faces of the panel frames with the result that the panels when not in use may be stacked in a compact manner without interference on the part of the brackets.

A further object of the invention is to provide a concrete wall form which is generally of new and improved construction and may be manufactured or produced at a comparatively low cost.

Other objects of the invention and the various advantages and characteristics of the present wall form will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary perspective of a concrete wall form embodying the invention;

2

Figure 2 is an enlarged fragmentary perspective illustrating in detail the design and construction of the devices for releasably locking the loop equipped ends of the combined tie and spreader rods to the panels;

Figure 3 is a vertical transverse section showing the manner in which the inner bolts of the releasable locking devices may be utilized to space the two series of abutting panels a maximum distance apart;

Figure 4 is a vertical transverse section showing the manner in which the outer bolts of the devices may be utilized to space the two series of panels a minimum distance apart;

Figure 5 is a vertical transverse section showing the manner in which the outer bolts of the locking devices on one series of panels and the inner bolts of the locking devices on the other series of panels may be employed or utilized to space the two series of panels an intermediate distance apart; and

Figure 6 is a section of one of the releasable locking devices.

The wall form which is shown in the drawings constitutes the preferred form or embodiment of the invention. It is adapted for use in connection with the formation of a concrete wall (not shown) and comprises a pair of opposed series of upstanding abutting panels 7, a plurality of combined tie and spreader rods 8, and a plurality of devices 9 for releasably locking the ends of the combined tie and spreader rods to the panels.

The two series of panels 7 are spaced apart as shown in Figures 1 to 5, inclusive, and are adapted, as well understood in the art, to have concrete poured therebetween. After setting of the concrete the panels are removed and the projecting ends of the tie and spreader rods are severed.

Each of the panels 7 comprises a rectangular wooden frame 10 and a facing 11 of plywood or other suitable material. The facings 11 of the panels are rectangular and are connected by nails or other attaching devices (not shown) to the front face portions of the frames 10. The frames embody vertically extending side pieces 12, horizontally extending top pieces 13, horizontally extending bottom pieces (not shown) and horizontally extending intermediate crosspieces 14. When the form is in its operative or wall forming position the side pieces are arranged in abutting relation, as shown in Figure 1, and are temporarily secured together by wooden connecting strips 15 or other suitable means. As shown in Figure 1, the connecting strips 15 fit against the outer faces of the panel side pieces 12 and are nailed in place.

The combined tie and spreader rods 8 extend horizontally between the two opposed, spaced apart series of panels and are all of uniform or the

same length. They are formed of any suitable metal and serve in conjunction with the devices 9 to hold the two series of panels in spaced apart relation during pouring of concrete therebetween. Preferably there is one combined tie and spreader rod for each pair of opposed crosspieces 14. The ends of the combined tie and spreader rods extend through holes 16 in the facings 11 of the panels 1 and embody outwards of the panel facings closed loops 17. The latter are horizontally elongated and extend vertically. The interiors of the loops constitute transverse openings through the ends of the rods 8. The holes 16 are located directly above the crosspieces 14 of the panel frames 10 and are preferably positioned 15 midway between the vertically extending frame side pieces 12.

The devices 9 for releasably locking the loop equipped ends of the combined tie and spreader rods 8 to the panels are associated with the panel frames 10 and comprise brackets 18, inner bolts 19 and outer bolts 20. As shown in the drawings, there are two devices 9 for each combined tie and spreader rod 8. The brackets 18 are in the form of one-piece plate metal stampings and are applied to the central or intermediate portions of the crosspieces 14 of the panel frames 10. They serve slidably to support the bolts 19 and 20 and comprise rectangular plates 21 which fit flatly against and extend lengthwise of the upper faces of the crosspieces 14. The brackets 18 are permanently secured in place by means of nails 22 which extend through holes 23 in the bracket plates 21 and are driven into the crosspieces 14. The width of the bracket plates 21 corresponds to the width of the crosspieces. The plates 21 are arranged so that the inner side edges thereof are in abutment with the outer faces of the panel facings 11. Certain ends of the plates 21 are bent upwards to form upstanding flanges 24. The latter extend at right angles to the bracket plates and have the inner end edges thereof in abutment with the outer faces of the panel facings 11. They are arranged and positioned transversely of the crosspieces 14 and serve to strengthen or reinforce the brackets 18 as a whole. The portions of the bracket plates 21 that are immediately inwards of the other ends of the plates are struck or deflected upwards to form channel forming parts 25. Such parts extend transversely of the bracket plates and are arranged in parallel relation with the upstanding flanges 24. They consist of flat horizontally extending top walls 26 and vertically extending side walls 27 and define open ended channels 28 which are in alignment with the holes 16 in the panel facings 11 and are adapted to receive the loop equipped ends of the combined tie and spreader rods 8. The inner ends of the channel forming parts 25 of the brackets 18 fit against the hole defining portions of the panel facings 11 and coat with the inner ends of the upstanding flanges 24 to prevent transverse tilting or rocking of the crosspieces 14 with respect to the facings 11. The portions of the outer margins of the bracket plates that are between the flanges 24 and the channel forming parts 25 are provided with extensions 29 and these are bent downwards at right angles to the plates and lap the outer faces of the crosspieces 14 of the panel frames 10. The inner bolts 19 overlie, and are spaced above, the inner portions of the bracket plates 21 and extend lengthwise of the plates. They are formed of flat strip metal stock and are mounted for lengthwise sliding movement. Certain ends of the inner bolts extend

through, and fit slidably within, rectangular apertures 30 in the inner ends of the upstanding flanges 24 and embody outwards of such flanges upstanding right angle heads 31. The other ends of the inner bolts have rounded or tapered extremities and extend through, and fit slidably within, aligned rectangular apertures 32 in the inner ends of the side walls 27 of the channel forming parts 25. They are adapted in connection with use of the inner bolts to extend through and become interlocked with the closed loops 17 at the ends of the combined tie and spreader rods 8. The inner bolts 19 of the releasable locking devices 9 are adapted to be used when it is desired to space the two series of abutting panels a maximum distance apart, as shown in Figures 2 and 3. In assembling the form the panels are manipulated into place and then the combined tie and spreader rods 8 are positioned so that the loop equipped ends thereof are disposed within the inner ends of the channels 28 and in alignment with the apertures 32. Before positioning the rods 8 the inner bolts 19 are slid in the direction of their heads 31 in order to shift the rounded ends thereof out of traversing relation with the channels 28. After positioning the rods 8 in the aforementioned manner the inner bolts 19 are slid longitudinally in the opposite direction in order to cause their rounded ends to pass through and become interlocked with the closed loops of the ends 17 of the rods. After sliding of the inner bolts into their operative position (see Figures 2 and 3) such bolts lock the loop equipped ends of the rods to the brackets 18 and thus secure the two series of abutting panels in fixed spaced apart relation. When it is desired to remove the panels after a wall forming operation the inner bolts 19 are shifted in the direction of the heads 31 thereof in order to disengage the rounded ends from the loops 17. Rivets 33 extend through the central portions of the inner bolts 19 and are arranged so that the heads thereof coat with the channel forming parts 25 and the upstanding flanges 24 to limit inward and outward sliding movement of the inner bolts into and out of their operative position, and also maintain the inner bolts in connected relation with the brackets. The heads 31 provide striking surfaces whereby the inner bolts 19 may be driven by a hammer or other tool into their operative position. The outer bolts 20 of the releasable locking devices 9 are disposed outwards of, and in parallel relation with, the inner bolts 19. They are adapted to be used when it is desired to space the two series of abutting panels a minimum distance apart. As best shown in Figure 2, the outer bolts 20 overlie, and extend lengthwise of, the outer portions of the bracket plates 21. They are the same in form as the inner bolts and have certain ends thereof extending through and slidably in rectangular apertures 34 in the outer ends of the upstanding flanges 24. The portions of such ends of the outer bolts that are outwards of the flanges 24 are provided with upwardly extending right angle heads 35. The other ends of the outer bolts 20 have rounded or tapered extremities and extend through and fit slidably within aligned rectangular apertures 36 in the outer ends of the side walls 27 of the channel forming parts 25. When it is desired to use the outer bolts they are slid outwards, i. e., in the direction of their heads 35 in order to shift the rounded ends thereof out of traversing relation with the outer ends of the channels 28. Thereafter the combined tie and spreader rods 8 are manipulated so as to cause

the loop equipped ends thereof to be disposed in the channels 28. After so manipulating the rods 8 the panels 7 are shifted laterally until the closed loops 17 at the ends of the rods are in alignment with the rectangular apertures 36 in the outer ends of the side walls 27 of the channel defining parts 25. After such manipulation of the panels the outer bolts 20 are driven inwards, i. e., in the direction of the channel forming parts, in order to cause their rounded ends to extend through and become interlocked with the loops 17. To release the outer bolts 20 from the loop equipped ends of the combined tie and spreader rods 8 after a concrete pouring operation the outer bolts are slid or shifted outwards by driving them in the direction of their heads 35. Such heads form striking surfaces whereby the outer bolts 20 may be hammered into their operative position. Rivets 37 extend through the central portions of the outer bolts 20 and are so arranged that the heads thereof coact with the channel defining parts 25 and the upstanding flanges 24 to limit inward and outward sliding movement of the outer bolts and also permanently to connect the outer bolts to the brackets 18.

It is contemplated that the inner and outer bolts will be used selectively, depending upon what spacing of the two series of abutting panels is desired. If it is desired to have the two series of panels spaced a maximum distance apart the inner bolts 19 are used, as shown in Figures 2 and 3. Should it be desired to have the two series of panels spaced a minimum distance apart the outer bolts 20 are used, as shown in Figure 4. In the event that it is desired to have the two series of panels spaced an intermediate distance apart the outer bolts 20 of the releasable locking devices at one side of the form and the inner bolts 19 of the releasable locking device at the other side of the form are used, as shown in Figure 5. In assembling the form the panels 7 are positioned to form two opposed laterally spaced series, as shown in Figure 1. Thereafter the combined tie and spreader rods 8 are arranged so that the closed loops 17 at the ends thereof are disposed within the channels 28 in the parts 25 of the brackets 18. After such arrangement of the combined tie and spreader rods the inner or outer bolts are driven into place, depending upon what spacing of the two series of panels is desired. After driving of the selected bolts into place concrete is poured into the space between the two series of panels. Upon hardening of the concrete the panels are dismantled by sliding the used bolts into their inoperative position. After such sliding of the bolts the panels are free and may be shifted away from the concrete wall.

The herein described concrete wall form effectively and efficiently fulfills its intended purpose and may be assembled and dismantled with facility because of the design and construction of the releasable locking devices 9. Because the outer portions of the brackets of the releasable locking devices are substantially flush with the outer faces of the panel frames the panels may be stacked when not in use in a compact manner without interference on the part of the brackets. By reason of the fact that each of the releasable locking devices 9 includes a plurality of slidably mounted bolts it is possible to use combined tie and spreader rods of a standard or fixed predetermined length and at the same time obtain a variation or adjustment in the spacing apart of the two series of abutting panels. The construction and design of the releasable locking devices are

such that the form as a whole may be produced at a comparatively low cost.

The invention is not to be understood as restricted to the details set forth since these may be modified within the scope of the appended claims without departing from the spirit and scope of the invention:

Having thus described the invention what I claim as new and desire to secure by letters patent is:

1. A device adapted for use in connection with a wall form type panel in the form of a facing with a hole therethrough and a reinforcing beam on the outer face of the facing and adjacent the hole, and a combined tie and spreader member having one end thereof extending through the hole and provided with a transverse opening outwards of said hole, said device comprising a substantially rectangular bracket plate mounted on the side face of the beam that is nearer the hole, extending lengthwise of said beam and having at one end thereof an outwardly and transversely extending flange with an aperture therethrough and adjacent its other end an outwardly and transversely extending part forming in alignment with the hole an open ended channel for receiving said one end of the member and provided in the side walls thereof with opposed apertures in alignment with the aperture in the flange, and a bolt extending slidably through the apertures and adapted when slid in one direction to extend through the opening in the member and effect a connection between said bracket plate and member.
2. A device adapted for use in connection with a wall form type panel in the form of a facing with a hole therethrough and a reinforcing beam on the outer face of the facing and adjacent the hole, and a combined tie and spreader member having one end thereof extending through the hole and provided with a transverse opening outwards of said hole, said device comprising a substantially rectangular bracket plate in the form of a one-piece plate metal stamping mounted on the side face of the beam that is nearer the hole, extending lengthwise of said beam and having at one end thereof an outwardly bent right angle flange with an aperture therethrough and adjacent its other end an out-struck transversely extending part of U-shaped cross section forming in alignment with the hole an open ended channel for receiving said one end of the member and provided in the side walls thereof with opposed apertures in alignment with the aperture in the flange, and a bolt extending slidably through the apertures and adapted when slid in one direction to extend through the opening in the member and effect a connection between said bracket plate and member.
3. A device adapted for use in connection with a wall form type panel in the form of a facing with a hole therethrough and a reinforcing beam on the outer face of the facing and adjacent the hole, and a combined tie and spreader member having one end thereof extending through the hole and provided with a transverse opening outwards of said hole, said device comprising a substantially rectangular bracket plate mounted on the side face of the beam that is nearer the hole, extending lengthwise of said beam and having at one end thereof an outwardly and transversely extending flange with an aperture therethrough and adjacent its other end an outwardly and transversely extending part forming in alignment with the hole an open ended channel for receiving

said one end of the member and provided in the side walls thereof with opposed apertures in alignment with the aperture in the flange, and a bolt extending slidably through the apertures, adapted when slid in one direction to extend through the opening in the member and effect a connection between said bracket plate and member, and provided with a laterally extending enlargement disposed between the said part and flange and coacting with the latter to limit sliding of the bolt relatively to the bracket plate.

4. A device adapted for use in connection with a wall form type panel in the form of a facing with a hole therethrough and a reenforcing beam on the outer face of the facing and adjacent the hole, and a combined tie and spreader member having one end thereof extending through the hole and provided with a transverse opening outwards of said hole, said device comprising a substantially rectangular bracket plate mounted on the side face of the beam that is nearer the hole, extending lengthwise of said beam, arranged so that its inner side edge is in abutment with the facing, having at one end thereof an outwardly and transversely extending full width flange with an aperture therethrough and its inner end in abutment with the facing, and having adjacent its other end an outwardly and transversely extending full width part having its inner end in abutment with the facing forming in alignment with the hole an open ended channel for receiving said one end of the member, and provided in the side walls thereof with opposed apertures in alignment with the aperture in the flange, and a bolt extending slidably through the apertures and adapted when slid in one direction to extend through the opening in the member and effect a connection between said bracket plate and member.

5. A device adapted for use in connection with a wall form type panel in the form of a facing with a hole therethrough and a reenforcing beam on the outer face of the facing and adjacent the hole, and a combined tie and spreader member having one end thereof extending through the hole and provided with a transverse opening outwards of said hole, said device comprising a substantially rectangular bracket plate mounted on the side face of the beam that is nearer the hole, extending lengthwise of said beam, having at one end thereof an outwardly and transversely extending flange with an aperture therethrough, having adjacent its other end an outwardly and transversely extending part forming in alignment with the hole an open ended channel for receiving said one end of the member, provided in the side walls thereof with opposed apertures in alignment with the aperture in the flange, and also having on the portion of the outer margin thereof between said flange and part a right angle extension in lapped relation with the outer face of the beam, and a bolt extending slidably through the apertures and adapted when slid in one direction to extend through the opening in the member and effect a connection between said bracket plate and member.

6. A device adapted for use in connection with a wall form type panel in the form of a facing with a hole therethrough and a reenforcing beam on the outer face of the facing and adjacent the hole, and a combined tie and spreader member

having one end thereof extending through the hole and provided with a transverse opening outwards of said hole, said device comprising a substantially rectangular bracket plate in the form of a one-piece plate metal stamping, fixedly mounted on the side face of the beam that is nearer the hole, extending lengthwise of said beam, having at one end thereof an outwardly bent right angle flange with an aperture therethrough, having adjacent its other end an outstruck transversely extending part of U-shaped cross section forming in alignment with the hole an open ended channel for receiving said one end of the member, and provided in the side walls thereof with opposed apertures in alignment with the aperture in the flange, and also having along the portion of the outer margin thereof that is between said flange and part an inwardly bent right angle extension in lapped relation with the outer face of the beam, and a bolt extending slidably through the apertures and adapted when slid in one direction to extend through the opening in the member and effect a connection between said bracket plate and member.

7. A device adapted for use in connection with a wall form type panel in the form of a facing with a hole therethrough and a reenforcing beam on the outer face of the facing and adjacent the hole, and a combined tie and spreader rod having one end thereof extending through the hole and provided with a closed loop outwards of said hole, said device comprising a substantially rectangular bracket plate in the form of a one-piece plate metal stamping, mounted on the side face of the beam that is nearer the hole, extending lengthwise of said beam, arranged so that its inner side edge is in abutment with the facing, having at one end thereof an outwardly bent full width right angle flange with an aperture therethrough and its inner end in abutment with the facing, having adjacent its other end an outstruck transversely extending full width part of U-shaped cross section, having its inner end in abutment with the facing, forming in alignment with the hole an open ended channel for receiving one end of the rod and provided in the side walls thereof with opposed apertures in alignment with the aperture in the flange, and also having on the portion of its outer margin that is between said flange and part an inwardly bent right angle extension in lapped relation with the outer face of the beam, and a bolt extending slidably through the apertures and adapted when slid in one direction to extend through the loop in the rod and effect a connection between said bracket plate and rod.
